UNITED STATES PATENT OFFICE

SAMUEL M. PANKEY, OF EMMET, ARKANSAS

OSCILLATING MOTOR

Application filed September 20, 1928. Serial No. 307,295.

This invention relates to well pumping apparatus and more particularly to an apparatus for pumping oil wells and the like by means of air pressure.

5 An important object of the invention is to provide in apparatus of this character an arrangement such that the chamber within the well from which the fluid is withdrawn is positively filled, this chamber being evacuated periodically during operation of the pump.

A further object of the invention is to provide a construction such that the same pumping apparatus will serve both as a means for 15 evacuating the container and for supplying air pressure to eject the contents thereof and the flow caused by the discharge is employed to regulate the reversal of operations.

A further and more specific object of the 20 invention is the provision in apparatus of this character of an arrangement such that a positive regulation may be had to insure a proper correspondence between intake and discharge functions of the casing.

25 A further object of the invention is the provision of a novel oscillating motor to be used in connection with such pumping apparatus.

A still further object of the invention is to provide an apparatus of this character 30 which may be very readily and cheaply installed, which will be durable and efficient in service, and a general improvement in the art.

These and other objects I attain by the 35 construction shown in the accompanying drawings, wherein for the purpose of illustration is shown a preferred embodiment of my invention and wherein:

Figure 1 is a side elevation showing well 40 pumping apparatus constructed in accordance with my invention;

Figure 2 is an enlarged side elevation of the 45 control mechanism, the parts being illustrated in solid lines in the well chamber discharging position and in dotted lines in the position in which the receptacle discharges to the tank;

Figure 3 is a vertical sectional view 50 through a portion of the well casing showing the pump chamber;

Figure 4 is a section on the line 4—4 of Figure 2.

Referring now more particularly to the drawings, the numeral 10 generally designates a well casing, the lower end of which 55 extends into fluid bearing strata 11 and is provided with the usual screen 12. Within the casing, I dispose a pumping chamber 13 which is in communication with the interior of the screen 12 through a check-valved inlet 14. Into the upper end of this chamber extend a discharge pipe 15, which projects to a point adjacent the bottom of the casing and is equipped with a check-valved inlet 16, and a control or operating pipe 17, which terminates adjacent the top of the casing and has its end portion reverted, as at 18, so that it is directed toward the top of the casing wall.

In combination with this structure, I provide an air pump 19, the intake of which is 70 connected through a conduit 20 with one port of a three-way valve 21. A second port of this valve is connected with the exhaust of the air pump by a conduit 22 preferably having arranged therein an accumulator 23. The third port of this valve is connected to the control conduit 17, which is preferably considerably reduced in size.

The numeral 24 generally designates a 80 storage tank for the reception of the discharge from the pumping apparatus, and, preferably supported by this tank, I provide a framework including spaced rectangular frames 25 connected at one end by a pivot shaft 26. Mounted upon this shaft is one end 85 of a lever structure 27, the opposite end of which supports a receptacle 28 having substantially the same capacity as the chamber 13. This receptacle has at its bottom a discharge outlet 29 having an automatic control valve 30 and a manual control valve 31. The automatic control valve 30 has directly connected thereto a trip rod 32 having a stop pin 33 coacting with a guide 34 through which the rod passes so that when the receptacle 28 is lowered to a predetermined extent, the automatic valve is lifted from its seat to permit the contents of the receptacle to discharge 90 into the tank 24 by a speed regulated by the manually controllable valve 31. Secured to 95

the receptacle by an adjustable link 35 is the operating handle 36 of the three-way valve, the link having a pin and slot engagement with the valve, as indicated at 37, to permit a delayed operation thereof.

5 The lever structure 27 is counterbalanced by a pivoted beam 38, the movement of which is defined by check bolts 39, 39^a. One end of this lever is linked to the lever structure, as indicated at 40, while the opposite end thereof is provided with a counterweight 41 of sufficient size to elevate the lever structure and receptacle when the receptacle is emptied.

10 The operation of the apparatus is as follows:—

15 Assuming the chamber 13 to be filled with liquid and the receptacle 28 to be empty and in an elevated position, the valve 21 is positioned to connect the discharge of the pump with the chamber, with the result that pressure is generated in the chamber, causing a discharge of the contents through the discharge line 15 to the receptacle. As the receptacle fills, the weight of the counterweight 20 is overcome and the receptacle lowers, with the result that the position of the three-way valve is reversed, so that a vacuum is formed in the chamber and the valve 30 of the receptacle is opened to permit discharge of 25 the receptacle into the tank 24. Thus, the chamber 13 is filling as the receptacle is being emptied and by the various adjustments, these operations can be synchronized, so that when the receptacle is emptied to a point permitting its return to an elevated position by the counterweight, the chamber 13 will be again filled, permitting the cycle of operations to 30 continue.

35 In order to facilitate manipulation of the apparatus, the intake line 20 has arranged therein a cut-off valve 42 and between this cut-off valve and the pump, a valved connection 43 is provided for placing the pump in communication with the atmosphere. Beyond this valve, a second connection 44 is provided for breaking the vacuum of the operating line. Similarly, a cut-off valve 45 is provided in the discharge line of the pump, preferably beyond the accumulator.

40 A counter 46 is preferably supported by the framework 25 and operated by the lever structure 27, so that the number of reciprocations of the receptacle can be accurately noted and the discharge from the well thus computed.

45 Since the construction hereinbefore set forth is capable of a certain range of change and modification without materially departing from the spirit of the invention, I do not limit myself to such specific structure except as hereinafter claimed.

50 I claim:—

55 1. In combination, a reservoir, a frame mounted on the reservoir, a receptacle hingedly mounted on said frame, discharging means for said receptacle, said discharging means

comprising a discharge outlet connected to said receptacle, a valve in said outlet, a valve stem secured to said valve, said stem having slidable engagement with said frame, and a stop on said stem engageable with said frame whereby to open the valve when the receptacle has reached a predetermined point in line of its movement in the frame, a fluid line discharging into said receptacle and operating means for said discharging means.

60 2. In combination, a reservoir, a fluid line, a supporting frame mounted on said reservoir, a lever pivotally secured at one end to said reservoir, fluid receiving means carried by said lever at the opposite end thereof, discharge means for said fluid receiving means, said discharging means comprising a discharge outlet connected to said receptacle, a valve in said outlet, a valve stem secured to said valve, said stem having slidable engagement with said frame, and a stop on said stem engageable with said frame whereby to open the valve when the receptacle has reached a predetermined point in line of its movement in the frame, operating means for said discharging means, said operating means engaging said frame when said fluid receiving means has swung downwardly to a predetermined point, and control means connected to said fluid receiving means whereby to transmit the power from said receptacle to an operated member.

65 3. In combination, a fluid discharging line, a reservoir, a frame upstanding from said reservoir, a receptacle swingingly carried by said frame, balancing means fulcrumed on said frame and connected to said lever, adjustable discharge means slidably engaging said frame, and connecting means engaging said receptacle whereby to actuate an operated member coactively with said receptacle.

70 4. In combination, a fluid discharge line, a fluid reservoir, a frame upstanding from said reservoir, a lever pivotally secured at one end to said frame and adapted for swinging movement within said frame, adjustable balance means carried by said frame and engaging said lever, stop means mounted on said frame whereby to limit the movement of said balance means, a fluid receptacle carried by said lever, adjustable discharge means for said receptacle, and connecting means mounted on said receptacle and engaging an operated member to operate said member coactively with the movement of said receptacle.

75 5. In combination, a fluid discharging line, a fluid reservoir arranged beneath said discharge line, a supporting frame upstanding from said reservoir, a receptacle swingingly mounted in said frame, adjustable balance means mounted on said frame and engaging said receptacle, a plurality of stop members carried by said frame whereby to limit the upward and downward movement of said bal-

ance means, adjustable discharge means for said receptacle, said adjustable discharge means slidably engaging said frame, and adjustable connecting means carried by said receptacle and engaging an operated member whereby to actuated said operated member upon movement of said receptacle.

5 In testimony whereof I hereunto affix my signature.
